(57) **CLAIM**

The ornamental design for a support for posts, as shown and described.

DESCRIPTION

FIG. 1 is a perspective view of my support for posts.

FIG. 2 is a side elevation view of my support for posts.

FIG. 3 is a top view of my support for posts

FIG. 4 is a bottom view of my support for posts.

FIG. 5 is a cross-sectional view of my support for posts taken along the lines 5-5 of FIG. 3.

FIG. 6 is a sectional view of the interior of my support for posts taken along the lines 6-6 of FIG. 5.

FIG. 7 is a side elevation view of my support for posts with a post installed.

FIG. 8 is the cross-sectional view of my support for posts of FIG. 5, with a post installed; and,

FIG. 9 is the sectional view of the interior of my support for posts of FIG. 6, with a post installed.

The dashed lines showing a post in FIGS. 7, 8, 9, are for illustrative purposes only and form no part of the claimed design.
